Des. 239,011

Patented Mar. 2, 1976

239,011

HANDLEBAR EXTENDER

Paul A. Hamasaki, 2322 Amberst Ave.,
Los Angeles, Calif. 90064

Filed Sept. 23, 1974, Ser. No. 508,383

Term of patent 14 years

Int. Cl. D12—11

U.S. Cl. D12—178

FIG. 1.

FIG. 2.

FIG. 1 is a perspective view of a handlebar extender from one side thereof showing my new design; and
FIG. 2 is a perspective view from the other side thereof.

I claim:

The ornamental design for a handlebar extender, substantially as shown.
